UNITED STATES PATENT OFFICE.

JOSEPH W. NORCROSS, OF LOCKPORT, NEW YORK.

TACKLE-BLOCK.

SPECIFICATION forming part of Letters Patent No. 251,926, dated January 3, 1882.

Application filed November 15, 1881. (No model.)

To all whom it may concern:

Be it known that I, JOSEPH W. NORCROSS, a citizen of the United States, residing at Lockport, in the county of Niagara and State of New York, have invented new and useful Improvements in Tackle-Blocks, of which the following is a specification.

This invention consists in the combination, with the inner metallic straps and with the outer metallic frames or straps, of tubular projections extending from the outer frames or straps through openings in the ends of the inner straps, an H-shaped distance-piece, and keys which extend through the tubular projections and through the H-shaped distance-piece, so that a firm and durable connection is obtained, while, when the keys are driven out, the frames and straps can readily be taken apart; also, in a lubricating-cup cast on or otherwise firmly connected with the inner strap, bearing against the inner surface of the outer strap or frame, said outer strap or frame being provided with a hole for the introduction of the lubricating material; further, in a sheave composed of a metallic rim, wooden disks fitting the interior of said rim, two metallic straps extending diametrically across the wooden disks at right angles toward each other, rivets projecting from the metallic rim and extending through the straps near their outer ends, a hub projecting from one strap through the wooden disks and through the second strap, a shoulder formed on said hub to form a bearing for the second strap, and pins cast solid with said hub and serving as rivets for securing the two straps firmly together.

This invention is illustrated in the accompanying drawings, in which Figure 1 represents a face view of my pulley-block. Fig. 2 is a transverse vertical section of the same. Fig. 2* is a similar section of a two-sheave block. Fig. 2** is a sectional plan of the connecting-piece for a two-sheave block. Fig. 3 is a perspective view of the breech end of one of the outer metallic frames. Fig. 4 is a horizontal section of the block in the plane αx , Fig. 2. Fig. 5 is a perspective view of the breech end of the inner metallic straps. Fig. 6 is a perspective view of the H-shaped distance-piece. Fig. 7 is a perspective view of one of the keys. Fig. 8 is a face view of the sheave. Fig. 9 is

a sectional side view of the two metallic straps used in the construction of my sheave. Fig. 10 is a diagram showing the connection of my pulley-block to the tiller of a vessel. Fig. 11 is a vertical section of the bracket and swivel-arm which I use in making this connection. Fig. 12 is a front view of the same. Fig. 13 is a plan or top view of a modified form of said bracket. Fig. 14 is a vertical section of the same.

Similar letters indicate corresponding parts.

In these drawings, the letter A designates my pulley-block; and B is the sheave, which has its bearing on the center-pin or axle C.

The block A is composed of outer metallic frames or straps, D D, inner metallic straps, E E, and wooden cheeks F F, which are placed between the outer frames and the inner straps. At the breech of the block the outer straps or frames, D, are provided with tubular projections $a a$ and with noses $b b$, Figs. 3 and 4. These noses hug the edges of the inner straps, and the projections $a a$ extend through apertures $c c$, Figs. 2, 4, and 5, in the inner straps, and in order to produce a firm connection I use an H-shaped distance-piece, G, and keys H. A perspective view of said distance-piece is shown in Fig. 6 and a sectional plan view in Fig. 4. It consists of two tubular bars, d d, and transverse connecting-bars e.

By referring to Fig. 4 it will be seen that the projections $a a$ of the outer straps or frames extend between the tubular bars $d d$, so that the keys H can be made to pass through said tubular bars and through the projections $a a$, and if the keys are inserted a firm connection is effected and at the same time the parts can be readily separated by removing the keys.

It will be readily seen from this description that the outside frames or straps can be keyed together with the inner straps without using the distance-piece G; but I use the distance-piece in order to strengthen the connection. It is obvious that the same connection may be applied to the head end of the block.

Each of the inner straps, E E, is provided with a lubricating-box, f, Fig. 2, which is cast solid with or otherwise firmly attached to the same. These lubricating-boxes extend through the wooden cheeks F, and their outer edges bear tight against the inner surfaces of the

outer straps or frames so as to prevent the escape of the lubricating material. In these outer straps or frames are holes which are closed by plugs *g*, and through which the boxes *f* can be charged with the lubricating material. The axle or center-pin *C* extends through the inner straps into the lubricating-boxes *f*, so that the bearing-surfaces can be easily lubricated by keeping up a supply of a suitable lubricant in the boxes *f*. For two-sheave or multiple blocks I use a connecting-piece, *O*, such as shown in Figs. 2* and 2**. It consists of a head, *r*, which fits between the inner straps, *E** *E**, and from which extend tubular projections *s* *s*, through apertures in said straps. These tubular projections connect with **H**-shaped distance-pieces *G**, in the manner already described.

The sheave *B* consists of a metallic rim, *h*, the inner periphery of which is slightly tapering outward, (see Fig. 2,) while its outer periphery is provided with a groove, *i*, for the reception of the rope. Into the interior of the rim *h* are placed two wooden disks, *j*, and on the outer surface of each of these disks is placed a metallic strap, *k*, which extends diametrically across, and is provided with holes *ll*, to engage with pins *m m*, Fig. 2, which project from the rim *h*, and which form rivets for connecting the straps firmly to said rim. One of these straps is provided with a hub, *n*, Figs. 2 and 9, which extends through the wooden disks *j*, and is provided with pins *oo*, Fig. 9, so that these pins form rivets, by means of which the two straps can be firmly connected. By these means the rim *h*, the disks *j*, and the straps *k* can be firmly united without requiring much time or labor.

For the purpose of connecting my pulley-block to the tiller *I*, Fig. 10, or to any other part in a vessel, I use a bracket, *k*, Figs. 11 and 14, a pin, *L*, which has its bearing in said bracket, a tube, *M*, which fits this pin and swivels on the same, and an arm, *N*, which extends from said tube, and is provided with a hole, *q*, to receive the pin *r'*, Fig. 2, at the front ends of the pulley-blocks. If the bracket *K* is to be secured to the tiller it is made in the form shown in Figs. 11 and 12; but if said bracket is to be secured to the deck of the vessel, Fig. 10, it is made in the form shown in Figs. 13 and 14. By providing the said tube *M* with the arm *N* the connection with the pulley-block can be made very easily, and when thus connected the block can accommodate itself to the motions of the rope, and the danger of chafing the rope is avoided. This construction of bracket, how-

ever, for connecting the pulley-block with the tiller I do not here claim, as such will form the subject-matter of a separate application for Letters Patent.

60

What I claim as new, and desire to secure by Letters Patent, is—

1. The combination, substantially as hereinbefore described, of the inner metallic straps, the outer metallic frames or straps, the tubular projections extending from the outer frames or straps through openings in the ends of the inner straps, and the keys which extend through the tubular projections.

65

2. The combination, substantially as hereinbefore described, of the inner metallic straps, the outer metallic frames or straps, the tubular projections extending from the outer metallic frames or straps through openings in the ends of the inner straps, the **H**-shaped distance-piece, and the keys which extend through the tubular projections and through the **H** shaped distance-piece.

70

3. The combination, with the inner and outer straps, of the lubricating-cup cast or otherwise attached to the inner surface of the inner strap, and covered at its open end by the fixed outer strap, the latter having a perforation communicating with the cup, which is closed by a removable plug, all substantially as and for the purpose described.

75

4. The cup *f*, connected with the inner surface of the inner strap, *E*, and projecting through the wooden cheek-piece *F*, in combination with the fixed outer strap, *D*, forming a cover to the cup and confining the wooden cheek-piece in place, substantially as and for the purpose described.

80

5. The combination, substantially as hereinbefore described, of the metallic rim *h*, the wooden disks fitting the interior of said rim, the pins *m m*, projecting from the rim, the straps *k*, extending diametrically across the disks and provided with holes to engage with the pins *m m*, the hub *n*, extending from the first strap through the wooden disks and provided with a shoulder which bears the second strap, the pins *oo*, projecting from the hub, and the holes in the second strap to engage with said pins.

85

In testimony whereof I have hereunto set my hand and seal in the presence of two subscribing witnesses.
